ELECTRICAL RELAY SYSTEM

Sherman B. Hall, Brockway, Pa., assignor to
Westinghouse Electric Corporation, East Pittsburgh, Pa., a corporation of Pennsylvania

Application May 7, 1946, Serial No. 667,980

3 Claims. (Cl. 175—320)

1

My invention relates to an electric system and more particularly to a system of control for obtaining a positive action on a mechanical element from electromagnetic means substantially unaffected by vibration.

The vibrations on a torpedo often interrupt circuits in the electric control of a torpedo thereby affecting the reliability of the operation of the elevator rudders or steering rudders, or some other element.

One broad object of my invention is the provision of circuit means so arranged that the operating effect of a particular circuit is not affected by the temporary opening or closing of contacts due to vibration.

Another object of my invention is the provision of an electrical lock-in relay system for accomplishing positive and reliable action of the elevator rudders of a torpedo in spite of the opening or closing due to vibration of the contacts in the control circuits for the rudders.

The objects recited are merely illustrative of my invention. Many other objects and advantages will become more apparent from a study of the following specification and the accompanying drawing, in which:

The single figure is a diagrammatic showing of my invention as applied to the depth control of a torpedo.

In the figure the rudders are considered at the right which represents the aft end of the torpedo. Nose-up operation of the torpedo thus causes the pendulum P to swing counterclockwise whereas nose-down operation will cause the pendulum P to swing clockwise. It is, of course, apparent that the pendulum actually hangs vertically, except for such effect the hydrostatic device H may produce on the pendulum, and that the angular movement is merely with reference to the torpedo housing T.

After the torpedo is under way in the water buses 1 and 4 are energized and, assuming for the moment that the torpedo is at the proper depth and traveling with the proper aspect angle so that the pendulum is in the neutral position shown, then a circuit is established from bus 1 through conductor 8, contacts 3, the up elevator solenoid UE to the bus 4.

As the torpedo nose moves to a small nose-up position from the horizontal position assumed, the movable contact 5 on the pendulum makes contact with the fixed contact 6, whereupon a circuit is established from the conductor 1 through contacts 5 and 6, actuating coil 7 of relay I and conductor 8 to bus 4. Relay I closes contacts 9

2

thereby energizing the actuating coil 10 of the elevator rudder control relay IV.

The operation of this relay IV causes the opening of contacts 3 and the closing of contacts 11. The up-rudder solenoid UE is thus deenergized and the down rudder solenoid DE is energized. The operation of relay IV also causes the closing of contacts 13 whereupon a circuit is established from bus 1 through conductor 12, contacts 13, actuating coil 14 of the relay II, contacts 15 of the relay III to the bus 4.

The operation of relay II closes the contacts 16 whereupon the energization of relay IV is made independent of the circuit through contacts 9 and thus indirectly of contacts 5 and 6. This is an important feature of my invention.

It will be noted that the operation of relay II also closes the contacts 19. The energization of relay II is thus made independent of the position of contacts 13. Vibration that might open contacts 13 is not likely at the same instant to open contacts 19. Even if the opening of contacts 13 and 19 might occur at substantially the same time, the inherent inductive time constants are such that no erroneous action can take place on the elevator rudders.

There is considerable vibration on a torpedo; the result is that contacts 5 and 6, especially when contact is first made, open and close due to vibration. Relay I may even open and close the contacts 9 because of vibration.

When contacts 5 and 6 first engage, relays I, IV and II operate in very rapid succession so that contacts 16 are in closed condition before any circuit interruptions can take place at contacts 5 and 6, or contacts 9. Further, the inherent inductive time constants of relays I, II and IV is such that momentary interruption of the magnetomotive force resulting from the connection of the coils to the buses 1 and 4 will not alter the down rudder position. Still further, the inductive time constants and the mechanical sizes of relays I, II and IV are different so that the probability of all the contacts 5 and 6, 9, 16 and 11 being open at the same time and for a sufficient time period to alter the down rudder position, at the time when the down rudder position is wanted, can, for all practical purposes, be ruled out.

When the torpedo swings through the horizontal position from the nose-up position to the nose-down position relay I is deenergized and as soon as contact 5 engages with the stationary contact 17, a circuit is established from bus 1

through contacts 5 and 17 and actuating coil 18 of relay III to bus 4.

Operation of relay III opens the contacts 15 and thereby deenergizing relay II. Contacts 16 and 19 are thus opened. Since contacts 9 are already open, the relay IV is deenergized. The up rudder solenoid UE is thus energized by the closure of contacts 3.

Again the vibration of the torpedo, for the same reasons above pointed out, does not affect the up rudder operation during the interim needed.

With my control circuit, it is possible to provide "close caging" on the depth control, that is, contacts 5 and 17 may be so spaced that but a small travel of contact 5 is necessary to make contact with either contacts 6 or 17. With my control, no resilient contacts are needed at the contact assembly comprising the contacts 5, 6 and 17. Resilient contacts produce a force on the pendulum thus altering the control effect of the pendulum.

While I have shown but one embodiment of my electric control system, I do not wish to be limited to the particular showing made but wish to be limited only by the scope of claims hereto appended.

I claim as my invention:

1. In a system of control, in combination, a circuit to be controlled, switching means for controlling the energization of said circuit, a pair of supply terminals for supplying electric energy to the system of control, a solenoid for actuating said switching means, said solenoid having one terminal connected to one supply terminal and having the other terminal connected through two parallel circuits to the other supply terminal, a pair of switches one in each of said parallel circuits, a second solenoid having one terminal connected to one supply terminal and having the other terminal connected through two parallel circuits to the other supply terminal, a second pair of switches one in each of said last-named parallel circuits, one of said last-named switches being operable by the first solenoid and the other of said last-named switches being operable by the second solenoid, a third solenoid, means for connecting the third solenoid to the supply terminals, one of said two first-named switches being operable by the last-named solenoid and the other being operable by said second-named solenoid.

2. In a system of control, in combination, a circuit to be controlled, switching means for controlling the energization of said circuit, a pair of supply terminals for supplying electric energy to the system of control, a solenoid for actuating said switching means, said solenoid having one terminal connected to one supply terminal and

having the other terminal connected through two parallel circuits to the other supply terminal, a pair of switches one in each of said parallel circuits, a second solenoid having one terminal connected to one supply terminal and having the other terminal connected through two parallel circuits to the other supply terminal, a second pair of switches one in each of said last-named parallel circuits, one of said last-named switches being operable by the first solenoid and the other of said last-named switches being operable by the second solenoid, a third solenoid, means for connecting the third solenoid to the supply terminals, one of said two first-named switches being operable by the last-named solenoid and the other being operable by said second-named solenoid, and a fourth solenoid disposed to be connected to said supply terminals for causing the energization of the second solenoid upon deenergization of the third solenoid.

3. In a system of control, in combination, a base subject to angular movement in a vertical plane, a pendulum mounted on the base for angular movement on a horizontal axis, a contact on the pendulum, a pair of closely spaced stationary contacts on opposite sides of the contact on the pendulum, whereby relatively small swings of the pendulum from a neutral position will make contact with either one or the other 30 of said stationary contacts depending on the direction of the swing of the pendulum, a pair of supply terminals one being connected to the contact on the pendulum, a pair of solenoids connected to the respective stationary contacts 35 and the other supply terminal to thus be selectively energized by the swing of the pendulum, three other solenoids, switch contacts operable by one of said first two mentioned solenoids for energizing the first of the last three mentioned solenoids, switch contacts operable by the first of said last three solenoids for energizing the second and third of said last three solenoids, and switch contacts operable by second of the last three mentioned solenoids for energizing the first and second of the last three mentioned solenoids.
